END CLOSURE FOR A CONTAINER

John S. Bozek, Chicago, Ill., assignor to Continental Can Company, Inc., New York, N.Y., a corporation of New York

Filed Oct. 23, 1963, Ser. No. 77,108

Term of patent 14 years

(Cl. D58—26)

FIG. 1

I claim:

The ornamental design for an end closure for a container, as shown.
